UNITED STATES PATENT OFFICE.

FRANK BOWERS, OF DETROIT, MICHIGAN, ASSIGNOR, BY MESNE ASSIGNMENTS, TO DIAMOND POWER SPECIALTY CORPORATION, OF DETROIT, MICHIGAN, A CORPORATION OF MICHIGAN.

BOILER CLEANER.

Application filed November 30, 1917, Serial No. 204,556. Renewed November 6, 1922. Serial No. 599,559.

This invention relates to soot blowers and refers more particularly to blowers of the type having rotary units for directing jets of steam or the like for cleaning the tubes.

One of the objects of the invention is to provide a device for automatically operating the various units by power in contradistinction to the usual hand operation. The invention also resides in the provision of an electric control for the various units and the provision for automatically cutting off the steam supply during that portion of the rotation of the unit where it would be injurious to the baffles or other parts of the boiler; in the construction whereby the units are operated only during the period when they are directing the steam jets in the proper direction; in the provision of means for insuring the unit being rotated at all times when the valve to that particular unit is open; and in such other features of construction and arrangements and combinations of parts as will more fully hereinafter appear.

In the drawings:

Figure 1 is a diagrammatic side elevational view showing my invention applied to a boiler;

Figure 2 is an enlarged plan view of the controlling cylinder, laid out in a single plane;

Figure 3 is an enlarged view of one of the units taken at right angles to Figure 1.

Figure 4 is an end view similar to Figure 3.

Describing in detail the particular embodiment of my invention shown in the drawings, A designates a boiler which in the particular instance shown is of the Stirling type. In this type of boiler there are a plurality of upper drums A' connected to a lower mud drum A² by banks of tubes A³. The gases are compelled to travel up and down over the baffle A⁴ and beneath the baffle A⁵. For cleaning the soot off from the banks of tubes A³ there are employed a series of rotary blower units B, B', B², B³ and B⁴, although the invention is not limited to any particular number or arrangement of units. Ordinarily these units are operated by hand mechanism such as chains extending over pulleys or the like, and the present invention particularly con-

templates a power-operated mechanism for rotating the units at predetermined times and during the desired period. For this purpose each unit of the series is provided with an electric motor which is connected to the unit by suitable reduction gearing, such as the worm-wheel D and worm D', so that a slow and steady rotary movement is given to the unit whenever the circuit to that particular motor is closed. For operating each of the units in turn and also for operating successively each of the units of a series or battery of boilers the following control mechanism may be employed.

In the particular construction shown the control mechanism comprises a slowly rotating cylinder E driven by any suitable means, such as the motor E'. This cylinder has at one end a series of elongated contacts F, F' and F². There is one of these contacts for each of the three boilers. (not shown, herein referred to as 1, 2 and 3, and the contacts are arranged in alignment so that whenever the cylinder E is being rotated one or the contacts F will be in electrical connection with the main line of contact G. Near the opposite end of the cylinder a somewhat similar series of elongated contacts H, H' and H² are arranged, the last-mentioned series of contacts, however, being out of alignment so that only one of them can at any time engage the corresponding contacts I, I' and I² which lead to the main valves of the boilers 1, 2 and 3 respectively.

In addition to the elongated series of contacts F, F' and F² and H, H' and H² the cylinder E is provided with individual contacts J, J', J², J³ and J⁴ which successively register upon rotation of the cylinder with the individual contacts K, K', K², K³ and K⁴ which close the circuit to the individual motors C', C', C², C³ and C⁴ of the blower units B, B', B², B³ and B⁴.

The operation of the control cylinder as above described is as follows: Assuming that the cylinder is rotating toward the left, that is, in the direction of the arrow in Figure 2 the blower units of boiler number 1 will be first automatically operated, each unit in succession as follows: On the initial turning of the cylinder one of the series of contacts F, F', etc., will be engaged by the contact

- G, one of the contacts K, K', etc., will engage the corresponding contact J, J', etc., and one of the contacts I, I', I² will engage the corresponding contact H, H', or H².
- 5 This will first result in energizing the electro magnet L, the circuit being traced as follows: main lead X, conductor Z, contacts G and F, conductor Z', contacts H and I, conductor W, electro magnet L and main lead Y.
- 10 Said electro-magnet when energized, will withdraw the main valve M from its seat, permitting steam to pass in the various branch pipes N, N', N², N³, and N⁴. Energization of the electromagnet L will move the contact O into engagement with the contact O', closing a circuit leading to the various motors C, C' etc., which circuit may be traced as follows: main lead X, conductor Z, contacts G and F, conductor Z', contacts J and K, conductor U, motor C, conductor P, contacts O, O', main lead Y. The unit driven by motor C will operate until the cylinder E is rotated a sufficient distance to
- 15 operate the unit B through the desired period of time, whereupon the contact J will move out of engagement with the contact K and the contact J' come into engagement with the contact K', closing the circuit through the motor C' and operating the unit B'. Similarly the units B², B³ and B⁴ are operated one after another until each of the units of the boiler number 1 have been automatically rotated to clean the soot from
- 20 the tubes of that boiler. The continued rotation of the cylinder E in the direction indicated by the arrow then moves the contact H out of engagement with the contact I and brings the contact H' into engagement with the contact I', after which the various units of this boiler are operated in accordance with the description of that for boiler number 1. The blowers of boiler number 3 are then brought into operation automatically by the engagement of the contact H² with the contact I², after which the contacts for boiler number 1 again come into play and automatically repeat the cycle of operation. It will be understood that by simply
- 25 providing additional contacts F, H and J the cleaners for any number of boilers can be power-operated and automatically controlled from the same cylinder.
- 30 In boiler cleaners of the type above mentioned it is often undesirable to operate the unit through a complete circle, since in so doing the steam jets would be directed against the baffles or other parts of the boiler where they would be liable to produce injury. I therefore provide a novel arrangement for permitting the rotation of the units through an entire circle but automatically cutting off the steam to each unit during any predetermined period of its rotation. While
- 35 various constructions might be employed for

this purpose, I have found the following arrangement simple and practical for performing this function.

In detail the automatic cut-off consists in providing a cam Q rotating with each unit and adapted to force the corresponding cut-off valve R or R', etc., back against the tension of a spring S so as to permit steam to pass into the unit from its branch supply pipe as long as the cam is in engagement with the lug S' which is formed as a projecting end of the stem of the valve. As soon, however, as the cam passes out of engagement with the lug S' the spring will automatically close the valve. Therefore a continuous rotation of the unit through any number of complete turns can be made without in any way injuring the baffles or other parts of the boiler against which it is not desired to direct the steam jets.

85 A further feature of my invention resides in the arrangement for preventing the cutting or injuring of the boiler tubes by steam jets being accidentally directed against one spot when the unit is not being rotated. For this purpose an additional switch is employed which is so arranged that when the valve to any particular unit is opened the circuit will be closed to the motor for that particular unit so that it will continue to rotate even though the current to the cylinder should be accidentally cut off; that is, it will continue to rotate until the low point on the cam is reached when the valve will be automatically closed by the spring or steam pressure and the additional contact also automatically broken. For this purpose each of the lugs S' is provided with an additional contact T which will engage a contact T' and close the circuit to that particular motor independent of the cylinder as long as the enlarged portion of the cam holds the lugs S' back and the valve open. However, as soon as the motor has rotated the unit so as to bring the low point of the cam into registration with the lug S' and thus release the latter the engagement between contacts T and T' will be automatically broken.

90 The source of electrical energy is from the main lead X back through the various mechanisms to the main lead Y. Assuming that the cylinder is first turned to bring the contact F into engagement with the contact G it will simultaneously bring the contact J into engagement with the contact K and the contact H into engagement with the contact I. The direction of the current is then from the main lead X from the source of energy, such as a dynamo or other source (not shown) down through the conductor Z to the contact G through the conductor Z', contact J, contact K and conductor U to the motor C and down through the conductor P to the contact O'. aneously the circuit is connected through the contact F, conductor Z', contact H, contact I, conductor W to the return main lead Y. The closing of this circuit energizes the magnet L thereby attracting the armature so as to open the valve M and also bring the contact O into engagement with the contact O' which closes the circuit between the conductor P and the main lead Y. Thus the motor C will be energized and at the same time as it rotates, the cam Q will force the valve R open and hold the contacts T and T' engaged. This same cycle of operations will continue for each of the motors C, C', C², C³ and C⁴ after which the contacts F and H will pass out of engagement with the contacts G and I and the contacts F' and H' pass into contact with the contacts G and I', after which the blowers of the second boiler will be operated, the motors of this set corresponding to motors C, C', etc., receiving current from contacts K, K', etc., through conductors U', U'^a, etc.; and after this cycle of operations has been completed, contacts F² and H² will respectively engage contacts G and I² and the blowers of the third boiler will be operated, the respective motors of this set receiving current from contacts K, K', etc., through conductors U², U^{2a}, etc. The second and third boilers are provided with valves corresponding to valves M which are operated respectively from contacts I', I² through conductors W', W². For the sake of clearness the duplication of these second and third series leading to the second and third sets of rotary blower units is not repeated in detail in the drawings, it of course being understood that there are a second and third boiler and blower units for the same corresponding to that shown in Figure 1.

Various changes, however, in the details of construction and arrangements and combinations of parts can be made within the scope of my invention.

What I claim as my invention is:

1. In a boiler cleaner, the combination with a plurality of blower units for each of several boilers, of power-operated means for rotating said blower units, and an electric control for automatically bringing into operation in succession the various units for cleaning one boiler and then the units for cleaning another boiler of the series.
2. In a boiler cleaner, the combination with a plurality of blower units adapted to discharge steam jets or the like, of an electric control for automatically connecting the various units so as to cause their successive rotation, and means independent of said electric control for insuring the rotation of the units at all times when the supply is open thereto.
3. In a boiler cleaner, the combination with a plurality of rotary blower units, of

a driving means associated with each of said units, means applying steam to said units, and means for automatically energizing the several driving means in succession.

4. In a boiler cleaner, the combination with a plurality of rotatable blower units, of motors respectively arranged to drive said units, means supplying steam for said units, circuits for the respective motors, and a driven controller member for successively energizing said circuits. 70

5. In a boiler cleaner, the combination with a battery of boilers, and a plurality of rotatable blower units associated with each of said boilers, of driving motors respectively associated with said units, a main circuit for the motors of each of said boilers, branch circuits for the respective driving motors of each boiler, a driven controller, means carried by said controller for successively closing said main circuits, and means upon the controller for successively closing the branch circuits while the corresponding main circuit is closed. 80

6. In a boiler cleaner, the combination with a rotatable blower unit and a driving motor therefor, of a valve controlling the steam supply to said unit, a normal circuit for said motor, a supplemental circuit for said motor, an actuated controller for periodically closing the normal motor circuit, and means for closing or breaking the supplemental circuit according as said valve is open or closed. 90

7. In a boiler cleaner, the combination with a plurality of blower units, of a normally closed main control valve for said units, individual normally closed control valves for the same, automatic means for periodically opening said main control valve and automatic means for successively opening said individual valves during each open period of the main control valve. 100

8. In a boiler cleaner, the combination with a plurality of rotative blower units, of a normally closed main control valve for said units, individual normally closed control valves for the units, automatic means for periodically opening said main control valve, means for successively rotating the blower units during the open periods of the main control valve, and means for opening the individual control valve of each unit during a portion of each revolution thereof. 110

9. In a boiler cleaner, the combination with a plurality of rotative blower units, of a normally closed main control valve for said units, individual normally closed control valves for the units, automatic means for periodically opening said main control valve, means for successively rotating the blower units during the open periods of the main control valve and mechanism associated with each unit and actuatable by rotation thereof for opening the corresponding indi- 120

125

130

vidual valve during a portion of each revolution of the unit.

10. The combination with a boiler of rotative blower units, of a normally closed main control valve for said units, individual normally closed valves for the units, automatic means for periodically opening said control valves, means for successively rotating the blower units during the open periods of the main control valve and mechanism associating with each unit and actuatable by rotation thereof for opening the corresponding individual valve at regular intervals.

11. In a boiler cleaner, the combination with a plurality of blower units, of a normally closed main control valve for said units, individual normally closed control valves for the units, valve controlling means whereby said main control valve may be periodically opened, and means automatically acting after the first said means starts to act for successively opening said individual valves during each open period of the main control valve.

25 12. In a boiler cleaner, the combination with a plurality of blower units, of a normally closed main control valve for said units, individual normally closed control valves for the units, a movable control member, means for moving said control member,

means responsive to movement of the control member for unseating the said main control valve, means also responsive to movement of the control member for automatically successively opening said individual valves, the first said means being adapted to maintain the main control valve unseated during the said successive operation of the said individual control valves.

35 13. In a boiler cleaner, the combination with a plurality of blower units, of a normally closed main control valve for said units, individual normally closed control valves for the units, a movable control member provided with a plurality of controlling elements, one of said elements being relatively long in comparison to the others, means controlled by said relatively long element and responsive to movement of the said control member for unseating the said main control valve, means controlled by the others of said elements and also responsive to movement of the said control member for automatically successively opening said individual valves, the first said means being adapted to maintain the main control valve unseated during the said successive operation of the said individual control valves.

40 45 50 55 In testimony whereof I affix my signature.
FRANK BOWERS.
